UNITED STATES PATENT OFFICE.

EDWARD LARSON, OF GRAND FORKS, NORTH DAKOTA.

CAR-DOOR OPERATOR.

1,399,627.

Specification of Letters Patent.

Patented Dec. 6, 1921.

Application filed April 27, 1920. Serial No. 376,974.

To all whom it may concern:

Be it known that I, EDWARD LARSON, a citizen of the United States, residing at Grand Forks, in the county of Grand Forks 5 and State of North Dakota, have invented certain new and useful Improvements in Car-Door Operators, of which the following is a specification.

This invention relates to door operating apparatus and more particularly to opening 10 and closing mechanism for sliding doors.

The object of the invention is to provide a sliding door with supporting and operating mechanism whereby rigid tracks and 15 rollers are dispensed with and sticking of the door prevented.

Another object is to provide such mechanism whereby the door may be operated with very little exertion.

20 Another object is to provide mechanism of this character which is very inexpensive and yet thoroughly efficient for the purpose for which is intended.

With the foregoing and other objects in 25 view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

35 In the accompanying drawings:

Figure 1 represents a side elevation of a sliding door equipped with this improved operating mechanism.

Fig. 2 is a top plan view thereof; and 40 Fig. 3 is a detail vertical section taken on the line 3—3 of Fig. 1.

In the embodiment illustrated a door frame 1 is shown surrounding a door opening 1^a which is adapted to be closed by a 45 sliding door 2. The frame 1 is equipped on its outer face along its lower edge with rests in the form of brackets 3 spaced longitudinally and designed to support the door when in open or closed position.

50 The door 2 has secured to one face transversely alined spaced keepers 4 and 5 in which are fulcrumed levers 6 and 7 said levers being shown fulcrumed midway their ends. Pivottally connected with one end of lever 7 55 is a link or bar 8, the other end of which

is pivoted to the upper portion of the door frame 1, as is shown at 9, and is spaced from said frame by a spacing sleeve 10 (see Figs. 2 and 3). The other end of lever 7 is pivottally connected with one end of a link or 60 bar 11, the other end of which is pivottally connected with the lower portion of the door frame 1 as shown at 12 and is spaced therefrom by a spacing sleeve 13. The pivotal connection of the link 11 at the bottom of 65 the door frame is in a plane to the left of the connection 9 of link 8.

The lever 6 has pivoted to one end a link or bar 14 the other end of said bar 14 being pivottally connected with the lower portion of door frame 1 at the left of and adjacent to the connection 12 of the bar 11 as 70 shown at 15, and is held spaced from said frame by a spacing sleeve 16.

The other end of lever 6 is pivottally connected to the lower end of the link or bar 17, the upper end of which is pivoted to the upper part of the door frame 1 at 18 and is held spaced from said frame by a spacing 75 sleeve 19.

A stop 20 is shown mounted on the right hand side of frame 1 for limiting the swinging movement of the door toward the right, and a hand grip 21, is secured to the lower right hand corner of the door to facilitate 80 its operation and when the door is swung to its extreme position to the left this stop engages link 11 and prevents the door from binding, in the same manner in which stop 20 operates when the door is moved to the 85 right.

A door supported in the manner above described and shown in the drawing will be held suspended by the toggle-like connected links and levers without requiring any 90 tracks or other hangers to support it, and when it is desired to open or close the door, a slight amount of exertion is required to swing it in either direction, all that is necessary being to grasp the handle 21 and 95 move the door either to the right or to the left, the lever and link connection operating to easily guide the door and hold it suspended in proper position without any danger of sticking of the door.

100 From the foregoing description, taken in connection with the accompanying drawings, the advantages of the construction and the method of operation will be readily apparent to those skilled in the art to which 110

the invention appertains and while I have described the principle of operation of the invention together with the device which I now consider to be the best embodiment thereof, I desire to have it understood that the device shown is merely illustrative and that such changes may be made as are within the scope of the claimed invention.

What is claimed is:—

- 10 1. The combination with a door frame and a sliding door mounted on one face thereof; levers fulcrumed intermediate their ends on said door; links pivotally connecting the end of said levers with the top and bottom of said frame.
- 20 2. The combination with a door frame and a sliding door; of operating and supporting means for the door comprising levers fulcrumed midway their ends on one face of the door, the fulcrums being in transverse alignment and spaced apart sufficiently to permit the free swinging of the levers without contacting with each other, the remote ends of said levers having links pivotally connecting them with the upper portion of the frame at longitudinally spaced points, and the adjacent ends of the said levers con-
- 25

nected by links with the lower portion of the frame at points adjacent each other.

3. The combination with a door frame and a sliding door; of operating and supporting means for the door comprising levers fulcrumed midway their ends on one face of the door, the fulcrums being in transverse alignment and spaced apart sufficiently to 35 permit the free swinging of the levers without contacting with each other, the remote ends of said levers having links pivotally connecting them with the upper portion of the frame at longitudinally spaced points 40 and the adjacent ends of the said levers connected by links with the lower portion of the frame at points adjacent each other, and stops carried by the door and the frame respectively for limiting the movement of the 45 door in opposite directions to prevent binding of the operating mechanism.

In testimony whereof I affix my signature in presence of two witnesses.

EDWARD LARSON.
